UNITED STATES PATENT OFFICE

121,645

DESIGN FOR A BRASSIÈRE OR SIMILAR ARTICLE

Benn Lewis, Maplewood, N. J., assignor to Jewel Mfg. Co., Inc., New York, N. Y., a corporation of New Jersey

Application June 5, 1940, Serial No. 92,833

Term of patent 7 years

To all whom it may concern:

Be it known that Benn Lewis, a citizen of United States and resident of Maplewood, in the county of Essex and State of New Jersey, has invented a new, original, and ornamental Design for A Brassière or Similar Article, of which the following is a specification, reference being had to the accompanying drawing, forming part thereof, and in which,

Fig. 1 is a front perspective view of a brassière, embodying my new design; and

Fig. 2 is an inside view of the same.

I claim:

The ornamental design for a brassière or similar article, substantially as shown.

BENN LEWIS.
